CHANNEL CEMENTING MACHINE

Wilbur L. MacKenzie, Beverly, Mass., assignor to United Shoe Machinery Corporation, Paterson, N. J., a corporation of New Jersey

Original application October 1, 1935, Serial No. 43,064. Divided and this application November 18, 1936, Serial No. 111,453. In Great Britain September 25, 1935

13 Claims. (Cl. 12—80)

This invention relates to machines for applying cement to the channels of shoe soles after the outseam has been formed, thereby to attach the channel flaps to the sole. The invention is herein illustrated as embodied in a machine of the extrusion type.

It is well understood in the manufacture of shoes that a seam for attaching the outsole may be formed at the bottom of a channel cut 10 in the sole and that after the seam has been formed, the channel flap may be cemented to the sole to hide the seam. Prior to the formation of the seam, the channel flap is lifted to facilitate the sewing operation, this usually being done 15 while the sole is in temper, and as a result, the flap is wrinkled transversely of its length, especially around the toe end of the sole. When the time comes for the application of cement to the channel, specifically to the channel base and the 20 inside of the channel flap, the flap may be dry and as a result quite stiff and hard. That being the case, the under surface of the flap provides a wrinkled surface. Obviously, the contour and outline of the sole are both irregular. Coating 25 shoe channels has commonly been performed by means of a rotary brush. With the rubber cements ordinarily employed, this sort of an apparatus is very successful. However, if the machine is to be used with cements of the pyroxylin 30 type or the polymerized chloroprene type, one form of which is commonly known as "Du Prene," then it is essential to avoid soiling the outside of the shoe because of the difficulty in removing such cements from the shoe upper, for example. 35 It is, furthermore, even more essential that exactly the desired quantity should be applied in order that there may be no squeeze-out when the channel flap is pressed into place.

Accordingly, an important object of the invention is to provide a channel cementing machine of the extruding type by means of which the cement may be applied expeditiously in just the desired quantities and without danger of soiling the adjacent parts of the shoe. 45 For a machine of this type, a nozzle will be employed which is adapted to enter the channel and to apply cement to the bed of the channel and also to the inner face of the channel flap. The operator will be able to support the shoe 50 manually so that the bed of the channel, which is formed in and supported by the sole, is held firmly against the nozzle. Because of the irregular nature of the channel flap, however, special provision must be made for holding the flap 55 in coating relation to the applying nozzle. To

this end, there is provided in the illustrated form of the machine, an oscillated flap-pressing finger by means of which the flap is supported in close relation to the side face of the nozzle and the pressure of the finger intermittently removed, 5 thereby to facilitate the feed of the shoe. As illustrated also, means is provided for controlling the oscillations both as to extent and as to the time of starting and stopping, the arrangement being such that the finger, when the driving force is removed, stands in an open position to facilitate presentation and removal of work from the machine. The illustrated arrangement of the machine provides a feed roll positioned at one side of the nozzle arranged to engage the 10 upper of the lasted shoe while the oscillated flap-pressing finger is positioned at the other side of the nozzle. 15

These and other features of the invention will be described in the following specification, taken 20 in connection with the accompanying drawings, in which

Fig. 1 is a side elevation of one embodiment of the invention, showing a machine with a side plate removed to disclose the parts within a 25 hollow frame;

Fig. 2 is a detail view, shown on a larger scale, of control mechanism for a flap-lifting finger;

Fig. 3 is an angular view of the operating tools, showing the presentation of a piece of work to 30 the machine;

Fig. 4 is a detailed section through an eccentric connection in the drive of the flap-lifting finger;

Fig. 5 is an angular view on a much larger scale of a nozzle, with a cover plate removed; 35

Fig. 6 is a similar view of a modified construction in which two plates are employed;

Fig. 7 is a side elevation of the nozzle shown in Fig. 5, with the cover plate in position;

Fig. 8 is a side elevation of the nozzle shown 40 in Fig. 6 with the plates in position;

Fig. 9 shows a modified form of the nozzle of Fig. 5;

Fig. 10 is an elevation looking at the leading edge of the nozzle shown in Fig. 9, and 45

Fig. 11 is a plan view of a fragment of a shoe sole, showing the flap in lifted position and illustrating the application of cement by means of a nozzle such as that shown in Fig. 8, the end portion of which is shown in a section taken on the line XI—XI of Fig. 8.

In the embodiment illustrated in the drawings, a machine frame 10 is mounted upon a pedestal 12 and supports a cement receptacle 14 as well as a pump casing 16 containing a gear pump by 50 55

which cement taken from the receptacle 14 is extruded under pressure through a flexible tube 18 to a nozzle 20 by which it is applied to the work. A piece of work, such as a shoe 22 mounted 5 on a last, has an outsole attached by stitches positioned at the apex or bottom of a channel cut in the sole. In the cutting of this channel, there is formed a channel flap 26 which is to be cemented to the bed 28 of the channel in the position which it occupied before the channeling cut is made. 10 The shoe is moved progressively past the nozzle 20 to cause the treatment of successive portions of the channel flap and the channel bed. Control of the quantity of cement extruded may be 15 effected in any desired way, as by a by-pass valve (not shown) adjusted by a thumb screw 29.

The frame 10 comprises parallel side plates 30 and 32 which are held in spaced relation by a plurality of shouldered bolts, such as the one shown 20 at 34, and some of which are utilized as pivots, as will be later described. At the top of the frame and between the plates 30 and 32 is mounted a block 36 which is held in position by bolts passing 25 through the holes 38 and which supports a rod 40 upon which there is mounted a nozzle carrier 42. This rod 40 may be adjusted in and out, and is held against turning by a pointed screw stud 44. The nozzle carrier is split at its upper end and held in the desired position on the rod by pinch 30 screws 46 (Fig. 3). A nozzle stem 51 has a flange 48 which is supported on spaced flanges 50 formed upon the carrier 42 and to which it is bolted. The connection between the flexible tube 18 and the nozzle stem 51 comprises a fitting 52 which contains a turn valve 54 and is provided with a base 56 secured in tight relation to the flange 48 of the nozzle stem 51 by screws (not shown). The upper end of the fitting is threaded in a T fitting 58 which supports a pressure gage 59 and is joined 35 to the tube 18. From Figs. 1, 5, and 7, it will be seen that the nozzle 20 itself has a flange 55 and a nipple 57. This nipple is received in a socket in the lower end of the stem 51 which has a flange 53 held to the flange 51 by screws.

Provision is made for feeding the work by 45 means of a rubber-tired roll 60 mounted on a stub shaft in an arm 62 which is pivoted on a pin 64 at the extreme right side of the machine so that the roll may be lifted slightly by the work to accommodate variations in the shape of the shoe. The pivotal movement of the supporting arm 62 is 50 guided by fitting this arm between the side plates 30 and 32. In order to drive the feed roll 60, the stub shaft on which it is mounted is connected by 55 pinions 66 with a counter shaft 68 journaled in the carrier arm 62. This counter shaft 68 is joined by miter gears 70 to another counter shaft 72 which, in turn, derives power from a main drive shaft 74 of the machine through spiral gears 76. 60 These gears rotate a short shaft 78 which is joined to the counter shaft 72 by an extensible shaft 80 containing universal joints. This arrangement gives complete freedom for up-and-down movement of the feed roll 60 without interfering with the drive.

In view of the fact that the channel flap 26 lies in all sorts of angular positions with respect to the channel bed 28, and the further fact that it is wrinkled and frequently stiff and dry, it has been 70 found desirable to press the flap against the side of the nozzle 20 by means of an oscillated flap-pressing finger 82. To this end, the finger is clamped in the lower arm of the bell crank lever 84 (Fig. 3) which is pivotally supported by 75 depending arms 86 secured to the nozzle carrier

block 42. A vibratory motion is imparted to the finger 82 by means of a horizontal rod 88 loosely received in a groove in the block 36 and connected to the upper arm 90 (Figs. 1 and 2) of a drive lever through toggle links 92 and 94. Thus, the flap is 5 pressed firmly against the nozzle but is intermittently released so that the work may be fed freely. At the point where the rod 88 is joined to the toggle link 92, it is pivotally supported upon a hanger 96 swinging from a pivot 98 in the block 10 36. A spring 100 surrounding the rod 88 bears against a portion of the nozzle-supporting block 36 and tends to return the finger 82 to a position spaced from the nozzle when there is no work in the machine, this movement being limited by a 15 collar 102. Thus, when the machine is at rest, there is always plenty of room to bring the channel flap into position between the finger and the nozzle or to remove it at the end of a cementing 20 operation. If the flap is turned well back against the sole, then the finger 82 serves also to lift it into cementing position.

The rod 88 is joined to the bell crank 84 by a pivot block 104 adjustably slidable along the rod and held in position thereon by nuts 106. As will 25 be seen from Fig. 4, this block 104 has a pivot pin 108 received in an eccentric sleeve 110 which may be rotated to determine the exact relation of the operative position of the finger 82 with respect to the nozzle so as to accommodate different thicknesses of channel flaps thereby firmly to support the flap in coating relation to the nozzle without hindering the feed of the work. A rough adjustment of this position, and, hence, of the limits of the range of oscillation, is secured by adjustment 30 of the pivot block 104 on the rod 88 by means of the nuts 106 but, when the operator changes from one class of work to another, such an adjustment as is provided by the nuts 106 is somewhat slow. There is provided, therefore, the eccentric sleeve 40 110, which may be held in adjusted position by means of a ratchet 112 formed on the sleeve and having saw-like teeth to receive a spring-pressed pawl 114. The saw-toothed ratchet 112 forms an 45 easily grasped handle for turning the sleeve 110 and, the inclination of its teeth being equal in both directions, the handle 112 may be turned either way, sliding over the beveled upper end of the pawl in so doing.

The oscillation of the rod 88 to vibrate the finger 50 82 is effected when the toggle links 92 and 94 are in line, as shown in Fig. 1, by means of the lever 90 on the lower arm 120 of which is a roll 55 coaxing with a serpentine-path cam 116 formed on or attached to a drive pulley 118 which is secured to the shaft 14. This lower arm 120 is outside the frame 30 and is joined to the upper arm of the lever 90 through a forked portion 122 extending around the edge of the frame. The design is such that the finger 82 is oscillated about 60 2400 times per minute and the flap is thereby pressed firmly against the side of the nozzle without interfering with the feed of the work. It will be noted that the drive shaft 74 is connected to the pump within the casing 16 by pinions 124.

For controlling the machine, there is provided a treadle rod 130 connected at its lower end to a treadle (not shown) and joined at its upper end to a plate 131 forked at its upper end to receive a vertical plate 132, the two being pivotally connected to one another and to a lever 154 to be later described. In the lower portion of the plate 131 is a slot 134 for the reception of a transverse pin between the branches of a forked lever 136, the left end of which is pivoted on a shouldered 75

bolt between the side plates 30 and 32 of the frame, and the right end of which is joined by a rod 138 to an operating lever 140 for the valve 54 in order thereby to control the flow of cement 5 through the nozzle 20. This operating lever 140 is secured to a rod 142 pivoted in a depending portion 144 of the block 36, and the rod is joined to the valve 54 through an intermediate shaft 146 having universal joint connections to the valve 54 10 and the rod 142. One of these universal connections is forked to enable the ready removal of the valve fitting 52 and is held in operative relation by a spring 148 surrounding the rod 142. A stop screw 150 determines the closed position of 15 the valve by limiting the upward movement of the operating lever 140 under the action of a spring 152 which is joined at its upper end to the block 36 and at its lower end to the forked lever 136. To limit the downward movement of the 20 treadle rod and the plates 131 and 132, the two are pivotally connected to each other and to a lever 154 having a portion 156 which abuts a stop 158 formed as a part of the frame member. The lever 154 swings on an eccentric portion of 25 its pivot pin, thus facilitating assembly of the machine by allowing this lever to be brought into correct relation to associated parts by turning the pin.

The same treadle rod 130 is arranged to control the vibrations of the flap-pressing finger 82 by either breaking or straightening the toggle links 92, 94. To this end, the upright plate 132 has a slot 160 which surrounds a pin 162 connecting the toggle links. When the treadle is depressed, the toggle is straightened and the oscillations of the lever 90 are transmitted to the finger 82. When the treadle is released and is raised by the spring 152, then the toggle is broken and the continuing oscillations of the lever 90 are 40 not transmitted to the rod 88. The shape of the lower portion of the slot 160 is such (Fig. 2) that movements of the lever simply oscillate the link 92 about its pivotal connection with the rod 88 without disturbing the plate 132 or the treadle 45 rod 130. At that time, the spring 160 will draw the finger 82 to an inoperative position, away from the nozzle.

The arrangement of the machine is such that the feed roll 60 is held resiliently against the work 50 by a connection to this same treadle rod 130 and, to this end, a lever 164 pivoted in the frame is slotted to receive a block 166 which is secured to the lever by a pin 168, this block surrounding the rod and being held against a stop collar 170 55 thereon by a spring 172 surrounding the treadle rod and bearing against the upper side of the block 166. The lever 164 is joined to the arm 62 which supports the feed roll 60 by a link 174. When the operator depresses the treadle, thereby 60 drawing the treadle rod down substantially vertically to a position illustrated in Fig. 1, he first moves the feed roll 60 into contact with the shoe already positioned with respect to the nozzle 20, straightens the toggle to cause oscillation of the 65 flap-pressing finger 82 and then opens the valve 54. Upon reverse movement of the treadle, the opposite action takes place and the valve is closed to stop the flow of cement and the finger 82 is stopped in open position, before the feed roll 60 70 is lifted from the work by the connection embodying the collar 170, the block 166, the lever 164 and the link 174. Thus, the shoe is always moving forward when the finger 82 is oscillated and when the cement is extruded through the nozzle.

75 The nozzle 20 is positioned in the machine as

shown in Figs. 1 and 3 in depending position and is inclined downwardly and forwardly with respect to the direction of movement of work presented thereto so that a removable plate 1180 secured to the outlet face of the nozzle lies approximately in a vertical plane passing through the axis of the feed roll. The lower end of the nozzle is tapered heightwise at 182 (Fig. 6) to aid in pushing it into the channel and is formed with a comparatively sharp leading edge 184 10 (Fig. 11) in which there is an outlet 186 (Figs. 5, 6, and 7) to deliver cement at the bottom of the channel. This cement also lubricates the nozzle, as it were, making it easier to feed the work. The nozzle also has a substantially triangular face 188 through which, at 192, emerges a passage 190 extending down through the nozzle. The outlet 186 communicates with the passage 190 through a branch passage 187. It is through this passage 190 that cement is 20 pumped at substantially constant pressure when the valve 54 is opened. As shown in Fig. 3, the shoe is moved away from the operator so that it approaches the leading edge 184 of the nozzle and so that the face 188 and the cover or deflector plate 1180 are upon the trailing face of 25 the nozzle.

It is desired, then, to cause the cement to be applied uniformly upon both the channel flap 26 and the channel bed 28 as well as in the bottom of the channel. To this end, the cover plate 1180 (Fig. 5), corresponding to the plate 1188 and positioned directly to overlie the outlet opening 192 of the passage 190, acts as a deflector and cooperates with the face 188 to 30 35 provide a transverse slot 194 (Fig. 7) forming lateral delivery passages or slots extending from the apex of the tapered end of the nozzle heightwise thereof to a point determined by a shoulder 196 on the cover plate. A series of cover plates 40 having this shoulder positioned at various distances from the pointed lower end may be utilized for channels $\frac{1}{4}$ -inch, $\frac{5}{16}$ -inch or $\frac{3}{8}$ -inch wide. Such nozzles, with their narrow outlet slots, show a notable flexibility in their ability to coat properly with channels, the depth of which varies between different parts of a shoe. Thus, even if the slot is longer than the channel is deep, the cement, due to its cohesiveness, will draw down from the upper end of the slot 50 to the upper edge of the work being coated without being extruded over the edge of the channel flap or the channel base, as the case may be. Were a series of holes employed instead of a slot, the cement extruded from the exposed upper holes would be forced over the edge of the channel flap or the channel base. The cover plate is also provided with a shoulder 198 which is intended to rest upon a shoulder 200 (Figs. 5 and 7) formed upon the nozzle, thereby to 55 assist in locating the cover plate in exact relation to the triangular face 188 of the nozzle. The area 197 between the two shoulders fits closely against the end face 189. The outline of the triangular portion of the cover plate is 60 slightly smaller than the corresponding outline of the face 188 to avoid any tendency of the edges of the cover plate to scrape off the cement just applied. Further to assist in locating the cover plate upon the nozzle, there may be provided a pin 202 which is received in a socket 204 in the nozzle. The cover plate will be held in position by a screw 206 having a threaded stem 210. The elliptical opening 192 formed where the passage 190 emerges in the face 188 65 70 75

is joined to the apex of the tool by means of a shallow groove 212 thereby insuring delivery of a sufficient quantity of cement to the bottom of the channel.

5. When the nozzle is in position in the machine, the channel flap 26 will be pressed against the plane surface 214, whereas the bed of the channel will be held against the opposite surface of the nozzle terminating in the edge 216. Under 10 some conditions, the bed 28 of the channel will not be flat but will be curved away from the plane of the bottom of the sole toward the shoe upper. This will be found in women's close-edged shoes and may result in a different curvature of the channel bed around the forepart than that which is in the shank. In order to adapt the nozzle for best operation with a close-edged shoe, it is found desirable to change the nozzle construction to that shown in Figs. 9 and 10 15 where parts similar to those shown in Fig. 5 have been given similar numerals to which 1000 has been added. This nozzle differs from that shown in Fig. 5 in having an inner or back surface which is curved inwardly to form a valley 25 terminating in the curved edge 220 which will be close to the shape of the channel bed around the forepart of the shoe and will approximate that found in the shank of the shoe. With this construction, the cover plate 1180 is also provided with a pointed end having a curved edge 30 222. It will be noted that the shoulder 1196 in the cover plate provided for this style of nozzle is not exactly parallel to the shoulder 1198 but deviates from that relation in accordance 35 with the need for providing outlet passages which will coat with the widths of the channel flap and the channel bed.

In constructing nozzles of the type shown in Fig. 5, it is common to do some hand filing where 40 the groove 212 joins the elliptical outlet opening 192 and sometimes this is done carelessly, bringing the opening nearer to one side edge than the other. This renders unequal the frictional 45 resistance offered to the cement flowing to the two sides and results in a somewhat uneven distribution of cement upon the two sides of the channel. It is avoided by forming a recess 224 (Figs. 6 and 9) in the end face of the nozzle which is separated from the edge of the nozzle 50 by a ledge 226 of uniform width, thus insuring an even distribution of cement. In the form shown in Fig. 9, this recess is joined to the tip of the nozzle by a groove 228 corresponding to the groove 212 in Fig. 6.

55. When the nozzle is to be employed for cements of the polymerized chloroprene type, one form of which is marketed under the name DuPrene, then a nozzle construction such as that shown in Figs. 6 and 8 may be advantageously employed 60 and has a pair of cover plates or deflectors 230 and 232. These deflectors, which are kept in alignment with one another by means of a stud 234 entering a socket 236, are mounted for slight lateral movement around a cylindrical portion 65 208 on the screw 206. To this end, the shoulder 240 on the inner plate 230 is spaced slightly from the shoulder 200 on the nozzle. The intermediate plate 230, having a surface 241 in close contact with the end surface of the nozzle, is also provided with a shoulder 242 corresponding to the shoulder 196 and, when positioned in cement-tight relation to the end face 188, forms a transverse slot 249 terminating in lateral passages 70 through which the cement is extruded upon the channel flap and the channel bed. This inter-

mediate plate is also provided with an elongated opening 244 opposite the outlet end of the passage 190 (Fig. 11) so that a portion of the cement passes directly to the slot 251 (Figs. 8 and 11) between the lower portion of the intermediate plate 230 and the face of the outer plate 232. This slot is limited by a shoulder 246 upon the rear face of the plate 230. Thus, two slots are formed providing two lateral passages upon each face of the nozzle, these being separated by the thin lower end 248 of the intermediate plate 230. The edges of the lower end 248 are serrated at 15 250 thereby to provide a sort of spreading action for the cement which is delivered to the work from the slot 249. The generally triangular lower end 248 of the intermediate plate is slightly smaller than the corresponding portion of the nozzle, while the outline of the lower end 252 of the cover plate 232 is even smaller and is rounded on the outer edges. This, together with 20 the opportunity for slight lateral displacement of the lower ends of the two cover plates with respect to the nozzle, reduces any interference 25 between the nozzle and the shoe to a minimum as the nozzle treats sharply curved portions of the channel. The cement extruded through the first slot 249 is effective to wet the surface of the leather of the channel flap and channel bed while that extruded through the second slot 251 is enabled thereby to stick even more readily to 30 these already coated surfaces, and to be applied in uniform and predetermined quantities.

The operation of the machine has already been set forth in connection with the description of the control devices joined to the treadle rod 130. 35

This application is a division of my application Serial No. 43,064, filed October 1, 1935, in which are claimed features of the extruding nozzle.

Having described my invention, what I claim as new and desire to secure by Letters Patent of 40 the United States is:

1. In a machine for cementing the channels of the soles of lasted shoes, a tapered nozzle adapted to be inserted in the channel of a shoe sole, a driven feed wheel on one side of the nozzle coacting with the upper of a lasted shoe presented thereto to carry the shoe edge past the nozzle, and means located on the other side of the nozzle for holding the flap against the nozzle. 45

2. In a channel cementing machine, a tapered nozzle adapted to be inserted in the channel of a sole on a shoe, a driven feed wheel coacting with the upper of a shoe presented thereto, and an oscillated finger for holding the flap against the nozzle. 50

3. In a channel cementing machine, a depending nozzle adapted to be inserted in the channel of a shoe sole, a driven feed wheel mounted on said machine for movement substantially vertically to bring it against the upper of a shoe presented to the nozzle, and means for pressing the channel flap against the nozzle. 60

4. In a channel cementing machine, means for applying cement to the channel, a pivotally supported flap-engaging finger holding the flap against the applying means, means including a spring to oscillate said flap-engaging finger, a driven feed wheel movable into and out of engagement with the upper of the shoe, and a treadle controlling said feed wheel and said finger, the treadle being arranged to lift the feed wheel and to release the finger-oscillating means so the finger can spring away from the work. 65

5. In a machine for cementing the channels of soles attached to shoes, a cement-applying nozzle 70

zle adapted to be inserted in the channel as a shoe is presented to the machine, a valve controlling the flow of cement to said nozzle, an oscillating flap-engaging finger to hold the channel flap against the side of the nozzle, and a treadle for bringing said finger into operative engagement with the work and for then opening the valve.

5. In a channel cementing machine, means for applying cement to the channel, a flap-engaging member holding the flap against the applying means, means for pivotally supporting said flap-engaging member on the machine, and means pivotally connected to said member for imparting an oscillation thereto, one of said pivotal means having an eccentric portion whereby the limits of vibration of the flap-engaging member with respect to the nozzle may be adjusted.

6. In a channel cementing machine, cement applying means, a flap-engaging finger mounted on pivotal means, means for imparting an oscillation to said finger including pivotal connecting means, one of said pivotal means having an eccentric portion and a serrated portion, and a pawl associated with said serrated portion thereby to hold the pivot in adjusted position.

7. In a channel cementing machine, cement applying means, a pivotally mounted flap-engaging finger, power operated means for oscillating said finger, an operative connection between said finger and said power operated means comprising a toggle, and means for straightening said toggle to cause the movement of the power operated means to be transmitted to the finger.

8. In a channel cementing machine, cement applying means, a pivotally mounted flap-engaging finger, power operated means for oscillating said finger, an operative connection between said finger and said power operated means comprising a toggle, and means for straightening said toggle to cause the movement of the power operated means to be transmitted to the finger.

9. In a channel cementing machine, cement applying means, a pivotally mounted flap-engaging finger, power operated means for oscillating said finger, an operative connection between said finger and said power operated means comprising a toggle, and means for straightening said toggle to cause the movement of the power operated means to be transmitted to the finger, said toggle-straightening means being provided with a slot constructed and arranged to permit idle movement of the toggle pivot when the toggle is broken without transmitting said movement to the straightening means.

10. In a channel cementing machine, cement applying means, a pivotally mounted flap-engaging finger, power operated means for oscillating said finger, an operative connection between said finger and said power operated means comprising a toggle, and means for straightening said toggle to cause the movement of the power operated means to be transmitted to the finger, the portion of said connection between the toggle and the finger being spring pressed to position the finger away from the nozzle, whereby when the toggle is broken the finger will be moved into inoperative position.

11. In a machine for cementing the channels of soles attached to shoes, a cement applying nozzle, means for forcing cement through said nozzle, a power-oscillated flap-lifting finger positioned at one side of said nozzle, and a power-driven shoe-engaging feed roll positioned at the other side of the nozzle.

12. In a machine for cementing the channels of soles attached to shoes, a cement applying nozzle, means for forcing cement through said nozzle, a power-oscillated flap-lifting finger positioned at one side of said nozzle, a power-driven work-engaging feed roll positioned at the other side of the nozzle, said feed roll being movable into and out of engagement with the work, control means for said oscillating finger, and means for moving the feed roll into contact with the work before oscillations are imparted to the finger.

13. In a machine for cementing the channels of soles attached to shoes, a cement applying nozzle, means for forcing cement through said nozzle including a control valve, a power-oscillated flap-lifting finger positioned at one side of said nozzle, a power-driven work-engaging feed roll positioned at the other side of the nozzle, said feed roll being movable into and out of engagement with the work, control means for said oscillating finger, and means for moving the feed roll into contact with the work before oscillations are imparted to the finger and before said valve is opened.

WILBUR L. MACKENZIE.
